UNITED STATES PATENT OFFICE.

ANDREW J. McDADE, OF NEW YORK, N. Y.

DESIGN FOR A CALENDAR-MOUNTING.

55,629.

Specification for Design.

Patented July 6, 1920.

Application filed September 24, 1919. Serial No. 326,086. Term of patent 14 years.

To all whom it may concern:

Be it known that I, ANDREW J. McDADE, a citizen of the United States, and a resident of the city of New York, borough of Brooklyn, in the county of Kings and State of New York, United States of America, have invented a new, original, and ornamental Design for a Calendar-Mounting.

Reference is to be had to the accompanying drawing in which the figure represents a perspective view of a calendar front embodying my new design.

I claim:

The ornamental design for a calendar mounting, as shown.

ANDREW J. McDADE.
